(57) **CLAIM**

The ornamental design for a spaceship keyboard, as shown and described.

DESCRIPTION

FIG. 1 is a perspective view of a spaceship keyboard showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an exploded perspective view of the spaceship keyboard; and,

FIG. 10 is an enlarged view of portion 10 shown in FIG. 1. The broken lines in the drawings depict portions of the spaceship keyboard that form no part of the claimed design. The dot-dash broken lines represent the boundary of the enlarged portion and form no part of the claimed design.
